US00D819100S

(12) **United States Design Patent** (10) **Patent No.:** **US D819,100 S**
(45) **Date of Patent:** **** May 29, 2018**

(54) **LINEAR ACTUATOR**

(71) Applicant: **TIMOTION TECHNOLOGY CO., LTD.**, New Taipei (TW)

(72) Inventor: **Yu-Chang Lin**, New Taipei (TW)

(73) Assignee: **TIMOTION TECHNOLOGY CO., LTD.**, New Taipei (TW)

(**) Term: **15 Years**

(21) Appl. No.: **29/577,366**

(22) Filed: **Sep. 12, 2016**

(51) **LOC (11) Cl.** **15-99**

(52) **U.S. Cl.**

USPC **D15/148**

(58) **Field of Classification Search**

USPC D12/345; D13/118, 158, 162, 184;

D15/1-5, 7, 9, 143, 148, 149, 199

CPC B66F 3/18; F16H 19/04; F16H 57/039;

H01F 7/066

See application file for complete search history.

(57) **CLAIM**

The ornamental design for a linear actuator, as shown and described.

DESCRIPTION

FIG. 1 is a perspective view of a linear actuator showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is second perspective view showing the linear actuator.
